UNITED STATES PATENT OFFICE.

HARRY B. PALMER, OF MENDHAM, NEW JERSEY.

PROCESS AND APPARATUS FOR CONCENTRATING ACTIVE DEPOSIT.

Application filed April 15, 1925. Serial No. 23,288.

This invention relates to process and apparatus for concentrating the active deposit of radioactive material upon a body or vehicle to be administered internally for the therapeutic value of the deposited material.

Certain objects and advantages of the invention will become apparent from the following description when taken in connection with the accompanying drawings in 10 which:

Figure 1 is a view showing, partly in section and partly in elevation, an apparatus for carrying out my invention.

Figure 2 is a detail view of a valve structure.

Referring to the drawings, the numeral 5 indicates a receptacle, preferably in the form of a glass bottle, into which may be introduced, through the neck 6 thereof, a quantity 20 of filtering solution such as potassium hydroxide indicated by the numeral 7. Within the neck 6 of the bottle there is fitted a stopper 8 through which a tube 9 passes, the tube 9 being projected, as shown, an appreciable distance into the potassium hydroxide which serves as a means for filtering or cleansing air, adapted, as will hereinafter more clearly appear, to be drawn into the container 5 through the tube. To the container 5 there is connected a tube 10 which is passed through a stopper 11 and projects an appreciable distance into a solution of 30 radioactive material 12 carried within a receptacle or container 13, into the neck 14 of which the stopper 11 is adapted to fit. The radioactive material may be in the form of radium chloride or suitable thorium preparations, and functions as a source of emanation which is adapted to be carried, by means 40 of pipes 15 and 16, into a storage vessel 17. This storage vessel is preferably constructed from glass and comprises an elongated body 18, the upper end of which is provided with a cup-like closure 19 having an opening 20 formed therein. The cup-like closure is adapted for the reception of a stopper 21, preferably constructed from rubber, the stopper being provided centrally with a recess or pocket 22 into which the upper or 50 closed end of a magazine 23 is adapted to be fitted and frictionally held while suspended in its vertical position, as shown. This magazine is preferably constructed from glass and is adapted for the reception of a plurality of pill-like carrying bodies 24 upon which the active deposit is, by the process

and apparatus embodying my invention, adapted to be concentrated. The pill-like bodies 24 may be either medicated or unmedicated and are intended to be administered internally for the therapeutic value of the active deposit concentrated upon the surface thereof.

In order to render the bodies 24 more or less conductive of electricity they may either 60 contain a certain amount of conductive material such as carbon for example or they may be provided with a thin film of a suitable conductive material. While I do not wish to limit myself to any particular dimensions in so far as the magazine 23 is concerned, I prefer to employ a magazine of such a length as to receive twelve pills. If the pills are to be administered in doses of one, three times a day, at the rate of three 70 a day and the magazine 23 is of such a length as to receive twelve pills, one filling of this magazine will, therefore, last four days in which case the magazine need be removed from the storage vessel 17 only once every 75 four days to replenish the supply of pills or carrying bodies.

The lower end of the elongated body 18 is bilged as shown to provide a chamber 25 within which is arranged a metallic electrode 85 26, to which the positive terminal of a suitable source of electrical energy, such as a battery 27, may be connected by means of a conductor 28. The negative terminal of the battery 27 may be connected to an electrode 90 29 by means of conductors 30 between which is interposed a suitable switch 31 for closing the circuit through the battery. The negative electrode 29 is centrally located within a rotary valve 32 and projects into a pair of 95 diametrically opposed pockets 33 formed in the valve 32. It will be noted that the negative electrode 29 projecting into the diametrically opposed pockets is adapted to contact with the lowermost pill 24, and it follows therefore that when the circuit is closed 100 through the battery by means of the switch 31 a negative potential is applied to the several pills.

In order to introduce the emanation, derived from the active material 12, into the storage vessel 17, I first set up within the vessel as nearly a perfect vacuum as is practicable, and to this end I employ a suction pump of suitable design indicated by the 110 numeral 34. This pump is provided with an exhaust nozzle 35 having a suitable check

2

valve 36 associated therewith, and is further provided with an intake pipe 37 within which is disposed a suitable check valve 38. The pipe 37 is adapted to be placed in communication with an exhaust pipe 39 through a two-way valve 40, when the valve is positioned as shown. The pipe 39 is suitably connected to the storage vessel 17, as shown, and is adapted to communicate with the interior thereof as will be readily appreciated. When the pump 34 is actuated the fluid content of the vessel 17 is removed, assuming that the valve 40 is positioned as shown, and discharged through the exhaust nozzle 35. The check valve 38, of course, so functions as to establish communication between the pipe 37 and the pump 34 when the operating handle 41 of the pump is withdrawn, whereas the valve 36, under such conditions, is so actuated as to sever communication between the pump 34 and the exhaust nozzle 35. When the operating handle 41 is moved to expel the fluid from the pump 34, the valve 38 is so actuated, as will be readily understood, as to prevent the return of fluid into the vessel 17, whereas the valve 36, under these conditions, is so actuated as to establish communication between the pump 34 and the nozzle 35, thus permitting fluid to be expelled from the pump 34 preparatory to another intake stroke of the handle 41.

After the vessel 17 has been reduced to substantially a vacuum, communication between the pipes 37 and 39 is severed by so rotating the valve 40 as to establish communication between the pipes 15 and 16. Upon establishing this communication air, due to the rarefied condition of the vessel 17, is drawn into the pipe 9 from which it emerges and thereafter bubbles up through the solution 7 which functions, as previously described, as a filtering or washing medium. The air thus washed is then transferred through the pipe 10 into the receptacle 13, whereupon it bubbles up through the solution 12 and passes on, carrying emanation with it, into the vessel 17 through the pipes 15 and 16. After filling the vessel 17 with emanation the valve 40 may be so moved as to sever communication between the pipes 15 and 16 without establishing communication between the pipes 37 and 39. Emanation thus introduced into the vessel 17 is allowed to remain therein until it is deemed advisable to introduce a new supply. Preparatory to administering a pill the circuit through the battery 27 is closed through the instrumentality of the switch 31, and inasmuch as the pills are subjected to a negative potential the active deposit is concentrated upon the exposed surface of the lowermost pill, the remaining pills being more or less protected against such action for the reason that they are confined within the magazine 23 as shown. Here it may be well to point

out that the pockets 33 are provided with raised portions or ribs 33' upon which the pills or carrying bodies are adapted to rest in order that substantially their entire surfaces may be exposed to the emanation when effecting concentration of the active deposit. After the treatment has been carried out to a sufficient degree the valve 32 may be rotated without breaking the seal afforded thereby, to dispense the coated pill, through the discharge opening 42. In rotating the valve to discharge the pill from the pocket 33, the diametrically opposed pocket is brought into position to receive the next succeeding pill and the coating and dispensing is carried on alternately until the supply of pills has become exhausted.

Having thus described my invention I claim:

1. A process of concentrating active deposit upon a plurality of carrying bodies in succession which consists in introducing said carrying bodies into a vessel, introducing emanation of radio active material into said vessel, subjecting said bodies to a negative electrical potential, shielding said bodies against active deposit, successively unshielding said bodies whereby such unshielded bodies may be successively subjected to said emanation.

2. An apparatus for concentrating active deposit upon a carrying body comprising a vessel adapted for the reception of a carrying body, means for introducing emanation of radio active material into said vessel, means for subjecting said body to a negative electrical potential in the presence of said emanation, and combined sealing and dispensing means adapted to be actuated to remove said carrying body from said vessel while maintaining said vessel closed.

3. An apparatus for concentrating active deposit upon a carrying body comprising a closed storage vessel adapted for the reception of emanation of radio active material and for the reception of a carrying body, means for subjecting the carrying body to a negative electrical potential in the presence of said emanation, and means for removing said carrying body from said vessel while maintaining said vessel closed.

4. An apparatus for concentrating active deposits upon carrying bodies comprising a storage vessel, a magazine adapted to be positioned within said vessel and adapted to carry a plurality of carrying bodies, means for introducing into said vessel emanation of radio active material, means for progressively removing said carrying bodies from said vessel, and means for subjecting said carrying bodies to a negative electrical potential prior to their removal.

5. An apparatus for concentrating active deposits upon carrying bodies comprising a vessel adapted for the reception of emanation

- tion of radio active material, a magazine arranged within said vessel and adapted to carry a plurality of carrying bodies, means for sealing said vessel, means for removing 5 said carrying bodies successively from said vessel while maintaining said vessel sealed, and means for subjecting said carrying bodies to a negative electrical potential within said vessel prior to their removal.
- 10 6. An apparatus for concentrating active deposits upon a carrying body comprising a vessel adapted for the reception of a carrying body, means for sealing said vessel, means for exhausting said vessel, means for 15 introducing emanation of radio active material into said vessel subsequent to exhaustion, means for subjecting said carrying body to a negative electrical potential, and means for removing said carrying body 20 from said vessel.
7. An apparatus for concentrating active deposit upon a carrying body comprising a vessel adapted for the reception of a plurality of carrying bodies, means for sealing 25 said vessel, means for exhausting said ves-
- sel, means for introducing emanation of radio active material into said vessel subsequent to exhaustion, means for shielding said carrying bodies from said emanation, means for unshielding said bodies successively, means for subjecting said bodies to a negative electrical potential, and means for removing said bodies successively from said vessel after having been subjected to 30 said negative electrical potential. 35
8. An apparatus for concentrating active deposits upon carrying bodies comprising a vessel adapted for the reception of emanation of radio active material, a magazine within said vessel and adapted to carry a plurality of carrying bodies, combined sealing and dispensing means for said vessel, adapted to be actuated to remove said carrying bodies successively from said vessel while maintaining said vessel sealed, and means 40 for subjecting said carrying bodies to a negative electrical potential within said vessel. 45

In testimony whereof, I have affixed my signature to this specification.

HARRY B. PALMER.
